UNITED STATES PATENT OFFICE.

JOHN McMURTRY, OF LEXINGTON, KENTUCKY.

IMPROVEMENT IN RIFLED PROJECTILES.

Specification forming part of Letters Patent No. 39,942, dated September 15, 1863; antedated October 16, 1862.

To all whom it may concern:

Be it known that I, JOHN McMURTRY, of Lexington, in the county of Fayette and State of Kentucky, have invented a new and useful Improvement in Projectiles for Smooth-Bore Guns, Cannon, &c.; and I do hereby declare that the following is a full, clear, and exact description of the construction and operation of the same, reference being had to the annexed drawings, making a part of this specification, in which—

Figure 1 represents a side elevation of my improved projectile. Fig. 2 represents a sectional elevation of the same, showing its "minié" feature, marked C. Fig. 3 represents a top or front view of same. Fig. 4 represents a top view of the same projectile as would be seen in a transverse section near the rear end, as indicated by dotted line on Fig. 5, with the channels B B made of equal depth from the circumference of the projectile between the rifles A A, commencing at the point where the twist begins, next the forward end, as shown, and gradually assume a uniform depth from the external circumference of the projectile, for the purposes hereinafter explained.

My improvement is intended to give, when shot from smooth-bore guns, cannon, &c., the same spinning or rotary motion as from those of rifled bore, and thereby secure the same accuracy as from the rifled gun, with greatly-increased force and range, to those from the rifled gun, &c. Recent experiments, both in the United States of America and England, demonstrated that there was nearly double the crushing force in the ball shot from the old sixty-eight-pound smooth-bore cannon as from the ball shot from the best one-hundred-pound rifled cannon; also, that the speed of the ball from the smooth-bore was over two thousand feet per second, whereas the speed of the ball from the rifled cannon was very little over one thousand feet per second. The scientific men give us the above facts, but not the reason therefor. The reason for this great disparity of speed and force is believed to be caused by the great resistance of the ball against the rifles of the rifled cannon, which also prevents the ball from receiving the full force of the powder until in the act of leaving the nozzle of the cannon. Consequently the expanded

and weakened force of the powder in the rifled cannon must necessarily be greatly inferior to that of the smooth-bore cannon, whose ball receives the full force of the powder from the breech instead of at the muzzle, as in the case of the rifled gun.

In my improved projectile, elongated substantially as shown in annexed drawings of same, I make two or more channels or rifles in same at equal distances from each other, commencing near the point of the projectile and running toward the rear end—say about one-third of the distance—straight, and then gradually assuming an increasing spiral curve toward the rear end, as will be readily understood by reference to annexed drawings of same at Fig. 1. By this arrangement of the rifles A A and channels B B the point of the projectile is left free from the action of the wind, which is received at the rear end of the ball in full force by the increasing spiral form of the rifles A A, thereby serving to give the spinning motion to the projectile so essential for accuracy, and also serving the same purpose as the feathers do on the Indian arrow—viz., giving accuracy to the point. I make the channels B B in two ways, as will be seen by reference to Figs. 3 and 4 of the annexed drawings, for the following reasons: I make the bottom of the channels B B in the form of a circle, terminating one side of same in coincidence with the exterior circumference of the projectile, for the purpose of avoiding the reaction of the rifles A A, &c., on the air consequent on the spinning motion of the projectile, as shown in Fig. 3. I also make the channels B B of equal depth from the exterior circumference of the projectile, as shown in the transverse section of same at Fig. 4 and the side elevation of same at Fig. 5, for the purpose of obtaining any benefit that may be gained from the reaction of the rifles A A on the air when made as shown in Figs. 4 and 5. This is done with reference to the received axiom that "action and reaction are equal, less the friction," which, if true, would cause the projectile made as Fig. 4 to pass through the air with very little resistance, which future experience alone can determine.

I do not claim the making of spiral grooves or channels on projectiles, for this may have been done in certain ways by others; but

What I claim as my invention, and desire to secure by Letters Patent, is—

1. The making on the sides of an elongated projectile two or more grooves or channels, with an increasing spiral twist toward the rear end of the projectile, substantially as described, and for the purposes set forth.

2. The above-named improvements in projectiles, in combination with the minie feature, substantially as described, and for the purposes set forth.

3. The above-mentioned improvements in

projectiles, in combination with the omission of that portion of the channels B B from the front of the projectile to that part of same when the twist of the channels commences, substantially as described, and for the purposes set forth.

January 8, 1862.

JOHN McMURTRY.
